FLAME ARRESTOR SAFETY DEVICE

Frans G. D. Muller, Houston, Tex.

Application April 18, 1935, Serial No. 17,002

9 Claims. (Cl. 220—89)

This invention relates to flame arresters, and more particularly to such arresters as are used in connection with oil storage reservoirs, for example.

Among some of the objects of this invention may be mentioned, the provision of a cover for flame arresters to prevent the ingress of foreign matter or substances in normal operation, the provision of means to exclude rain from the ar-
10 rester, the provision of a cover for the arrester which on the occasion of an actual flame or combustion taking place will be fusible so as to allow the flame to extend freely away from the ar-
15 rester, simplicity of construction and other ob-
jects not specifically enumerated.

I have attained the foregoing objects and others hereinafter pointed out in the specification by constructing a flame arrester having a vent for communication with the interior of a
20 container and a fusible cover associated there-
with.

In the drawing Fig. 1 illustrates in perspective parts of my invention with the cover omitted, Fig. 2 is a transverse section of the cover and frame work taken on the line 2—2 of Fig. 1, Fig. 3 is an elevation on reduced scale of the arrester in position, Fig. 4 is a plan view of the cover, Fig. 5 is a detail view showing the manner in which the cover is fastened to the supporting
30 structure. Fig. 6 is a fragmentary perspective showing one of the plates from which are built up the units providing the gas passageways of the arrester.

Considering the drawing in greater detail, the
35 flame arrester assembly is shown in Fig. 3 in relation to an oil storage tank 10, the tank being connected by a pipe 11 to a suitable flame arresting vent 12 with a fusible cover 13 at the top and a foraminous screening portion 14 connect-
40 ing the cover and the base of the vent. This construction is such that the tank may "breathe" allowing the pressures inside and outside the tank to be readily equalized, the foraminous member preventing foreign materials from passing into
45 the vent and keeping birds and other living ob-
jects from getting therein or about.

Fig. 1 shows in fragmentary perspective the parts of Fig. 3, the vent pipe 11 being flanged and secured by means of a plurality of bolts 15
50 or other means to the vent, breathing valve or other means 12. Mounted upon the top of the breathing valve is the flame arrester 16. This member comprises a plurality of parts composite-
ly making up the entire flame arresting body
55 and including a plurality of substantially ver-

tically extending passages 17 in communication with the interior of the container to be protected. These holes 17 are preferably obtained by slots in substantially flat plate members such as shown in Fig. 6, a plurality of the plate members being positioned together. As will be seen, the slots or grooves 17 are formed in one face of each plate member so that when the plate members are grouped together as in Fig. 1, the back of one plate will close the open sides of the 10 grooves in the previous plate to form the gas passageways. Cooling passages 18 are obtained by providing substantially horizontal members 19 which are separate from the vent openings. As illustrated, the upper member 19 contains vertical openings 20, allowing the cool air after being heated to pass upwardly above the vent openings.

The member 12 may be of any suitable construction and may be a mere pipe section or a breather valve. The flame arrester 16 is fastened in an upright position upon the member 12 in the example illustrated. The base 20 which secures these two members together is provided with a plurality of outwardly extending portions 21 which are bored to receive the upright bars 22. 20 Mounted upon the tops of the bars is a frame work 23 which may be substantially rectangular or of other shape in plan view having a peripheral portion 24 and a plurality of interconnecting arm portions 25. These latter portions extend upwardly to a common point 26, and are provided with projections or shouldered portions 30 which seat upon the tops of the bars 22 and are fastened thereto by wing nuts 32, secured on the rods by a screw threaded portion 33. A fusible cover member 13 is mounted on the frame work and is provided with portions 34 providing substantially tubular protuberances which engage the shouldered portions 30 of the frame work, thus creating a firm seating of these parts. The peripheral portions 40 of the cover 13 may or may not be crimped under the peripheral edge of the frame, depending upon the exigencies of its use.

The safety device of the present embodiment is such that in normal operation, i. e. so long as the 45 vapors from the interior of the member 11 are not ignited, the vessel to which it is attached will automatically equalize the pressures inside and outside and prevent explosions. The cover 13 precludes moisture or other foreign material 50 from passing down into the vent grooves and the foraminous member 14 aids in this while at the same time preventing birds or bugs or any other objects from getting into the apparatus. If the gases which are given off through the open- 55

ings 17 should become ignited by lightning or any other means, an explosion is prevented by the flame arrester keeping its parts so cool that the flame cannot be propagated down through 5 the grooves. An additional factor in this construction is the cover. The cover is preferably of light gauge aluminum, lead foil or analogous material so that when the flame burns for a short period the fusible material becomes heated and is 10 then melted, passing away and opening the top of the vent to the atmosphere so that the flames can pass upwardly with unobstructed passage to thereby additionally aid in precluding any possibility of the flame getting inside of the arrester.

15 While I have illustrated a preferred embodiment of my invention, it is to be clearly understood that variations in shape, construction etc. within the true spirit and scope of my invention are aimed to be covered by the hereto appended 20 claims.

I claim:

25 1. A safety device for oil storage tanks comprising in combination a vent having gas passages and air cooling passages in heat conducting relation, separate from each other, and extending substantially at right angles to each other; a plurality of supporting arms at the corners of said vent; a framework mounted upon said arms; a fusible cover on same framework; and a foraminous member interconnecting said cover and the 30 base of said vent.

35 2. A safety device for oil storage tanks comprising in combination a vent having gas passages and air cooling passages in heat conducting relation, separate from each other, and extending substantially at right angles to each other; a plurality of supporting arms at the corners of said vent; a frame work mounted upon said arms; and a fusible cover on said framework.

40 3. A safety device for oil storage tanks comprising in combination a vent having separate gas passages and air cooling passages in heat conducting relation; a plurality of supporting arms at the corners of said vent; a frame work mounted upon said arms; a fusible cover on said frame work; and means retaining said fusible cover and said frame work on said arm.

45 4. A safety device for oil storage tanks comprising in combination a vent having gas passages and air cooling passages in heat conducting relation, separate from each other; a plurality of supporting arms at the corners of said vent; a frame work mounted upon said arms; a fusible cover on said frame work; and wing nuts retaining said fusible cover and said frame work on 50 said arms.

5. A safety device of the class described comprising in combination a vent having gas passages and air cooling passages in heat conducting relation, separate from each other; a plurality of supporting arms at the corners of said vent; a frame work mounted upon said arms; and a fusible cover on said framework; said framework having a plurality of upwardly extending portions, and portions of said fusible cover engaging 55 said upwardly extending portions.

6. A safety device for oil storage tanks comprising in combination a vent having gas passages and air cooling passages in heat conducting relation separate from each other, and extending substantially at right angles to each other, a plurality of supporting arms at the corners of said vent, a fusible cover on said arms, and a foraminous member interconnecting said cover and the base of said vent.

7. A flame arrester having vent openings 20 through which inflammable gases are adapted to be projected outwardly, a fusible cover thereabove adapted to intercept objects and prevent them from entering said vent openings, said fusible cover being so positioned with respect to said vent openings as to permit relatively free normal operation of the arrester before the cover is fused and a greater freedom of escape of heat from the arrester after the cover is fused.

8. A flame arrester having vent openings 30 through which inflammable gases are adapted to be projected upwardly and outwardly, a heat destructible protecting device thereabove adapted to intercept objects and prevent them from entering said vent openings, said protecting device being so positioned with respect to said vent openings as to permit relatively free normal operation of the arrester before said protective device is 35 destroyed and a greater freedom of escape of heat from the arrester after the protective device is 40 destroyed.

9. A flame arrester having independent cooling and venting openings through which venting openings inflammable gases are adapted to be projected outwardly, a fusible cover thereabove adapted to intercept objects and prevent them from entering said vent openings, said fusible cover being so positioned with respect to said vent openings as to permit relatively free normal operation of the arrester before the cover is fused and a greater freedom of escape of heat from 45 the arrester after the cover is fused, so that the arrester will not become heated to the point where it will transmit a flame.

FRANS G. D. MULLER.
